CLAIM

The ornamental design for a motorcycle brake disc guard assembly, as shown and described.

DESCRIPTION

FIG. 1 is a rear perspective view of a design for a motorcycle brake disc guard assembly according to the present invention.

FIG. 2 is a right side view of the motorcycle brake disc guard assembly of FIG. 1.

FIG. 3 is a left side view of the motorcycle brake disc guard assembly of FIG. 1.

FIG. 4 is a rear view of the motorcycle brake disc guard assembly of FIG. 1.

FIG. 5 is a front view of the motorcycle brake disc guard assembly of FIG. 1.

FIG. 6 is a top view of the motorcycle brake disc guard assembly of FIG. 1; and,

FIG. 7 is a bottom view of the motorcycle brake disc guard assembly of FIG. 1.

The broken lines in the drawings depict environment and form no part of the claim.
